(57) **CLAIM**

We claim the ornamental design for a dispenser, as shown and described.

DESCRIPTION

FIG. 1 is a bottom perspective view of a dispenser showing my new design;

FIG. 2 is a rear view of the design of FIG. 1;

FIG. 3 is a front view of the design of FIG. 1;

FIG. 4 is a right side view of the design of FIG. 1;

FIG. 5 is a left side view of the design of FIG. 1;

FIG. 6 is a top view of the design of FIG. 1;

FIG. 7 is a bottom view of the design of FIG. 1 hereof;

FIG. 8 shows the top view of FIG. 6 with a broken line to indicate the plane upon which the sectional view in FIG. 9 is taken;

FIG. 9 is a cross-sectional view, taken in the direction of line 9-9 in FIG. 8; and,

FIG. 10 is a top perspective view of the design of FIG. 1. The broken lines in the drawings illustrate the portions of the dispenser that form no part of the claim.

1 Claim, 8 Drawing Sheets
